UNITED STATES PATENT OFFICE

SALIM N. MALLOUK, OF BROOKLYN, NEW YORK

DESIGN FOR AN EMBROIDERED BRIDGE-TABLE COVER OR THE LIKE

Application filed June 6, 1929. Serial No. 31,560. Term of patent 3½ years.

To all whom it may concern:

Be it known that I, SALIM N. MALLOUK, a citizen of the United States of America, and a resident of the borough of Brooklyn, Kings County, city and State of New York, have invented a new, original, and ornamental Design for Embroidered Bridge-Table Cover or the like, of which the following description, in connection with the accompanying drawing, is a specification.

The single figure of the drawing is a plan view of approximately one-fourth of an embroidered bridge table cover or the like, the exact quarter section being outlined by the inner dot and dash lines, showing my new design. The design shown in the representative illustration is repeated in the other three corners.

I claim as my invention:

The ornamental design for an embroidered bridge table cover or the like as shown and described.

SALIM N. MALLOUK.
